United States Patent Office

Des. 221,880

Patented Sept. 14, 1971

221,880

MODEL RACING CAR

Robert John Herd, Milton Malsor, England, assignor to
March Engineering Limited, Oxfordshire, England

Filed July 31, 1970, Ser. No. 24,246

Claims priority, application Great Britain Feb. 2, 1970

Term of patent 7 years

Int. Cl. D21—02

U.S. Cl. D34—15

FIG. 1 is a top plan view of the model racing car showing my new design;

FIG. 2 is a front elevational view thereof;

FIG. 3 is a right side elevational view of FIG. 1, the left side being a mirror-image thereof; and

FIG. 4 is a rear elevational view of FIG. 1.

I claim:

The ornamental design for a model racing car, as shown and described.
